UNITED STATES PATENT OFFICE.

DAVID A. HULTGREN, OF CHICAGO, ILLINOIS, AND CLARENCE TAYLOR, OF EAST ORANGE, NEW JERSEY, ASSIGNEES TO MASSEY CONCRETE PRODUCTS CORPORATION, OF CHICAGO, ILLINOIS, A CORPORATION OF VIRGINIA.

CRIBBING.

Application filed February 23, 1924. Serial No. 694,489.

To all whom it may concern:

Be it known that we, DAVID A. HULTGREN and CLARENCE TAYLOR, citizens of the United States, and residents, respectively, of Chicago, in the county of Cook and State of Illinois, and East Orange, in the county of Essex and State of New Jersey, have invented certain new and useful Improvements in Cribbing, of which the following is a full, clear, concise, and exact description, reference being had to the accompanying drawings, forming a part of this specification.

This invention relates to cribbing for use in constructing retaining walls such as employed to hold the fills and embankments of railways.

The object of the invention is to provide a retaining wall, the front face of which will be practically tight so as to prevent the escape of dirt or gravel therethrough, and which will consist of simple parts which may be easily assembled into a rigid wall.

It is believed the invention will be understood most readily from a description thereof taken in connection with the accompanying drawings, in which—

Figure 1 shows a face view of one form of applicants' retaining wall;

Figure 2 is a vertical section through the wall shown in Figure 1, taken on the plane represented by the line 2—2 of Figure 1.

Figure 3 is a perspective view of the headers employed in constructing the wall;

Figure 4 is a perspective view of one of the rear stretchers;

Figure 5 is a perspective view of one of the forward stretchers, and

Figure 6 is a section similar to that shown in Figure 2 through a portion of a wall in which a modified form of forward stretcher is employed.

Referring now to the drawings, in which like reference characters indicate like parts in the several views, 10 indicates the headers which are all of the same character, 12 the forward stretchers, and 13 the rear stretchers. The headers 10 are preferably substantially rectangular in cross section, as indicated in Figure 3, and are provided at each end thereof with oppositely disposed flanges 14, which form T-shaped heads, the heads at the opposite ends of the headers 10 being similar in construction and arrangement.

The forward stretchers 12 are preferably 55 rectangular in cross section at their ends where they rest upon the headers 10, but intermediate of the headers they are provided with the upwardly and downwardly extending flanges 15, as shown in Figure 5. 60

The rear stretchers 13 are preferably rectangular in cross section throughout their length, as indicated in Figure 4. If desired, however, the stretchers 12 may be employed at both the forward and rear sides of the retaining wall. It is, of course, to be understood that the headers and stretchers will preferably be formed of concrete or like material, as is usual in structures of this character, and will comprise such reinforcing 70 rods as are necessary to give them the required strength.

In constructing the wall, the headers 10 are disposed with the flanges 14 extending in a vertical direction, and ends of the 75 stretchers 12 or 13 are disposed between each one of the headers 10 and the next adjacent one.

Referring now to Figure 2, it will be noted that beginning at the bottom, the 80 stretchers 12 and 13 are disposed below the lowermost header bars 10. These will preferably be so arranged that the forward stretchers will be slightly higher than the rear ones so that the face of the wall will 85 be slightly rearwardly inclined. The lowermost header bars are positioned upon the stretchers with the flanges 14 projecting vertically immediately adjacent to the outer edges of the stretchers. The stretcher bars 90 will be arranged in substantially the same plane and spaced apart horizontally distances substantially equal to the length of the stretchers so that the ends of the headers 10 will overlie the abutting ends of the 95 stretchers. The stretcher bars are then placed upon the headers immediately adjacent to the flanges 14 at the ends thereof with their ends in abutting relation over the headers. This process is carried on, placing 100 the stretchers on top of the headers, and then the headers on top of the stretchers, in much the same manner as a rail fence might be constructed, until the wall has reached its required height. Due to the 105 simple character of the header and stretcher bars, the wall may be readily constructed by unskilled workmen, and, in fact, may be

readily constructed by a single workman if the individual bars are made of such a size that one man can handle them.

- When the wall is of considerable height, 5 say twelve feet or so, a secondary or supplemental course of headers and another course of stretchers may be provided at the rear of the first course, as indicated at the left in Figure 2. The headers of the 10 rear course will project between the rear stretchers 13 of the forward course with their ends projecting through sufficiently so that the flanges 14 of the rear headers will engage the forward faces of the rear stretchers 13 of the forward course. Another tier 15 of stretchers 13 will, of course, be provided at the rear of the headers of the second course in the same manner as used in connection with the first course.
- 20 If it should be desired to form an exceptionally high wall, two or even more supplemental courses of headers and stretchers may be provided, each course preferably being of a height less than the preceding 25 course. As the spaces between the headers and stretchers are filled in with dirt, gravel, or other material, the whole structure becomes firmly anchored together and the rear or supplemental courses will act to prevent 30 the forward course from being shoved outwardly by the pressure of the embankment.

As the headers are supported on the abutting ends of the stretchers and the stretchers are in turn supported on the headers, considerable weight is brought to bear on the 35 joints between the members at the bottom of the wall due to the weight of the headers and stretchers, and also to the pressure of the material placed therein, so that the 40 whole structure is firmly bound together. The space between the forward stretchers is practically closed by the upwardly and downwardly extending flanges 15 provided on the forward stretchers 12, thus preventing 45 the escape of dirt and gravel therebetween. It is to be understood, however, that the flanges 15 should not be of such a length as to permit them to ride on each other and thus prevent firm engagement of the headers 50 and stretchers where they overlap.

The forward stretchers 16, shown in Figure 6, differ from the stretchers 12 in that each has a single upwardly extending flange 17 instead of the upwardly and downwardly 55 extending flanges 15. It will be understood, however, that the flange 17 is of somewhat greater width than the flange 15 employed in connection with the stretcher 12. With 60 this construction, the upper edge of the flange 17 will be positioned below the forward edge of the stretcher above, and even though a slight crack is left, it will be so positioned that little or no dirt or gravel will escape therethrough.

65 It is to be understood that applicants con-

template slight modifications in certain features of the retaining wall herein disclosed and the invention, therefore, should be limited merely by the scope of the appended 70 claims.

Having thus described our invention, what we claim as new and desire to secure by Letters Patent of the United States is:

1. A retaining wall constructed of self-supporting cribbing comprising a plurality 75 of headers arranged in superposed spaced courses, a course of stretchers positioned between one course of headers and the next, each of said headers having T-shaped extremities arranged with the T-flanges disposed in a substantially vertical plane, each of said stretchers having a flat bottom surface across its entire width and having a single closure flange projecting upwardly 80 from the upper surface of said stretcher, said closure flange being of a depth substantially equal to the vertical thickness of the adjacent header, and all of said stretchers having their closure flanges notched back 85 from the ends of the stretchers for receiving said headers whereby the joints between adjacent stretchers of each course all occur in alignment with the T-shaped ends of said headers.

2. A retaining wall comprising a plurality 90 of headers arranged in superposed spaced courses, a course of stretchers positioned between one course of headers and the next, each of said headers having T-shaped extremities arranged with the T-flanges disposed in a substantially vertical plane, each 95 of said stretchers having a flat bottom surface across its entire width and having a single closure flange projecting upwardly from the upper surface of said stretcher, said stretchers being of a length equal to the horizontal spacing between adjacent tiers 100 of headers and having their closure flanges notched back from the ends of the stretchers for receiving the headers with the T-shaped 105 ends overlapping the joints between adjacent stretchers.

3. Cribbing of the class described, comprising a plurality of headers arranged in superposed spaced courses, a course of 110 stretchers positioned between one course of headers and the next, each of said headers having T-shaped extremities arranged with the T-flanges disposed in a substantially 115 vertical plane, each of said stretchers comprising a main body portion of rectangular cross section having a flat surface on one of its horizontal sides, and comprising a closure flange of rectangular cross section projecting from the opposite side with its outer 120 surface extending flush and in the same plane with the outer surface of said main body portion, said closure flanges being of sufficient depth substantially to engage the 125 flat underside of the adjacent stretcher, said 130

stretchers being of a length equal to the horizontal spacing between adjacent tiers of headers and having their closure flanges notched back from the ends of the stretchers
5 for receiving the headers with the T-shaped ends overlapping the joints between adjacent stretchers.

In witness whereof, we hereunto subscribe our names as follows:
Chicago, Illinois, January 26th, 1924.

DAVID A. HULTGREN.

East Orange, New Jersey, Feb. 16th, 1924.
CLARENCE TAYLOR.
